ENGINE STARTER GEARING

E. Elliott Hood, Elmira, N. Y., assignor to Bendix Aviation Corporation, South Bend, Ind., a corporation of Delaware

Application May 22, 1942, Serial No. 444,015

5 Claims. (Cl. 290—38)

The present invention relates to engine starter gearing and more particularly to an automatically operated detent for ensuring traversal of a starter drive pinion into mesh with a member of an engine to be started.

Various forms of detent have heretofore been used in connection with engine starter gearing of the automatically engaging type, to ensure the desired traversal of the pinion under adverse conditions. It is an object of the present invention to provide a novel detent arrangement which is efficient and reliable in operation while being free from interference with the cranking function of the drive.

It is another object to provide such a device in which the detent is arranged to be actuated simultaneously with the energization of the starting motor, and to be released when the drive is fully engaged.

It is another object to provide such a device in which the release of the detent is consequential to the assumption of the cranking load by the drive.

Further objects and advantages will be apparent from the following description taken in connection with the accompanying drawings, in which:

Fig. 1 is a semi-diagrammatic illustration of a starting system showing a preferred embodiment of the invention;

Fig. 2 is a diagrammatic representation of a variation of the electrical system shown in Fig. 1; and

Fig. 3 is a view similar to Fig. 1 of a further embodiment of the invention.

In Fig. 1 of the drawings there is illustrated an engine starting system including a battery 1 grounded at 2 and connected through a starting switch 3 and cable 4 to a starting motor SM which is grounded at 5 to complete the cranking circuit.

The motor is arranged to operate a power shaft 6 which drives a screw shaft 7 through gears 8 and 9, and a pinion 11 is threaded on the screw shaft for movement into and out of engagement with a gear 12 of the engine to be started.

According to the present invention a detent indicated generally by numeral 13 is arranged to oppose initial rotation of the pinion in order to ensure its traversal along the screw shaft into engagement with the engine gear. As here shown detent 13 comprises a magnetic plunger 14 and an electromagnet 15, the plunger being normally maintained free of the pinion by a retracting spring 16. A circuit is provided for actuating the

detent simultaneously with the application of current to the starting motor. As here shown this circuit comprises a relay 17 having an armature 18 connected by a lead 19 with the cranking circuit cable 4 and having a contact 21 normally in engagement with a stationary contact 22 which is connected by a lead 23 to the electromagnet 15, said electromagnet being grounded at 24 to complete the detent-actuating circuit.

10 Means for causing the release of the detent responsive to the assumption of the cranking load by the motor is provided comprising a control relay 25 having an armature 26 connected by a lead 27 with the detent circuit lead 19 and having a contact 28 normally in engagement with a fixed contact 29. A coil 31 connected by a lead 32 to the control relay lead 27 and grounded at 33 is arranged to attract the armature 26 and open contacts 28, 29 when the full battery voltage is applied to said coil. The relay 25 is so designed however that coil 31 will release the armature 26 and permit contacts 28, 29 to close when the voltage in the cranking circuit is reduced by the heavy current drain caused by the starting motor when it first assumes the cranking load.

Contact 29 of control relay 25 is connected by a lead 34 to coil 35 and fixed contact 36 of relay 17, coil 35 being grounded at 37 to complete the relay circuit. Coil 35 is constructed in any conventional manner as a comparatively slow-acting electromagnet which when energized attracts armature 18 to open contacts 21, 22 and close contacts 21, 36.

35 In the operation of this embodiment of the invention, starting with the parts in the positions illustrated, closure of the starting switch 3 by the operator completes the cranking circuit through the starting motor and causes the screw shaft 7 to be rotated thereby. Closure of the starting switch 3 also completes the detent-actuating circuit through lead 19, contacts 21, 22 and lead 23 to the electromagnet 15 thus causing the plunger 14 to engage the teeth of the pinion 11 and resist rotation thereof to ensure its traversal into engagement with the engine gear 12.

40 Closure of starting switch 3 also completes the circuits through coil 31 of relay 25, and coil 35 of relay 17. Coil 31, however, is effective to open contacts 28, 29 before coil 35 opens contacts 21, 50 22, due to the slow-acting character of coil 35, so that contacts 21, 22 remain closed.

When the pinion 11 reaches the end of its travel on the screw shaft 7, said shaft is constrained to rotate the pinion and assume the cranking load of the engine. The consequent momentary

stalling of the starting motor SM causes a very heavy current drain through the cranking circuit which substantially reduces the voltage applied to the coil 31 of relay 25. This reduction in voltage is arranged to permit closure of contacts 28, 29, and the consequent energization of coil 35 which attracts the armature 18 of relay 17, opening contacts 21, 22 and closing contacts 21, 36. The opening of contacts 21, 22 breaks the detent circuit whereby the plunger 14 is released from the pinion 11 by the retracting spring 16. Closure of contacts 21, 36 completes a holding circuit from lead 19 through coil 35 whereby the armature 18 is held down as long as the starting switch 3 remains closed, irrespective of the opening of contacts 28, 29 of relay 25. When the cranking operation is completed and the operator opens the starting switch 3, the parts return to their idle positions as illustrated.

In Fig. 2 of the drawings there is illustrated an embodiment of the invention incorporating a control relay which is dependent for its operation on variations in current flow in the cranking circuit. As there shown, a control relay 25' has a coil 31' connected in series in the cranking circuit, and an armature 26' carrying a contact 28' adapted to cooperate with a fixed contact 29' but normally held out of engagement therewith by a spring 30. The remaining parts are the same as shown in Fig. 1 and are similarly numbered.

In operation, closure of starting switch 3 energizes the starting motor, and at the same time actuates the detent 13 to oppose rotation of the pinion. When the pinion is fully meshed with the engine gear and the motor assumes the cranking load, the heavy current through the coil 31' causes the contacts 28', 29' to close, thereby energizing coil 35 of relay 17. Contact 21 is thus caused to leave contact 22 and engage contact 36, whereby the detent control circuit is opened and detent 13 is released.

In Fig. 3 of the drawings there is illustrated a starting system which provides for energization of the starting motor in two stages. During the initial stage, the voltage applied to the starting motor is reduced by a resistor in the starting circuit, which resistor is later short circuited, in order to apply full battery voltage during the cranking operation.

As here shown, the starting circuit comprises a battery 51 grounded at 52 and connected by a starting switch 53 to a cable 54 leading to a resistor 55 of suitable value for reducing the battery voltage to decrease the shock of engagement of the gear. A cable 56 connects the resistor 55 to the starting motor SM which is grounded at 57 to complete the starting circuit. Motor SM is arranged to actuate a power shaft 58 which drives a screw shaft 59 through gearings 61 and 62. A pinion 63 is threaded on the screw shaft 59 for movement into and out of engagement with an engine gear 64.

An electromagnetic switch 65 is arranged to short circuit the resistor 55 after the pinion 63 is fully engaged with the engine gear 64. Switch 65 comprises a contact 66 connected by a lead 67 to the starting circuit cable 54, a contact 68 connected by a lead 69 to the starting motor cable 56, and a bridging contact 71 mounted on a plunger 72 arranged to be actuated by a coil 73. One end of coil 73 is connected by a lead 74 to the lead 67, and the other end is connected by a lead 75 to the armature 76 of a control relay indicated generally by numeral 77.

An electromagnetic detent indicated generally

at 78 is provided for opposing rotation of the pinion 63 to ensure its meshing operation. This detent comprises a plunger 79 normally retracted from the pinion by a spring 81 but adapted to be moved into engagement with the teeth of the pinion by means of a coil 82. An actuating circuit for the detent 78 is provided comprising a lead 83 connecting the lead 67 to a coil 84 in the control relay 77. The opposite end of coil 84 is connected to the armature 76, and by a lead 85 to the detent coil 82 which is grounded at 86 to complete the actuating circuit. Armature 76 is provided with a contact 87 adapted to engage a fixed contact 88 which is grounded at 89, said contacts being normally held out of engagement by suitable means such as a spring 91.

Means are provided for causing release of the detent 78 when the starting motor assumes the cranking load, which means comprises a coil 91 in the relay 77, one end of which is connected to the lead 83 and the other end is connected by a lead 92 to the starting motor cable 56 so that the coil 91 is, in effect, arranged in parallel with the resistor 55. Coil 91 is thus energized by the voltage drop across the resistor 55 and when so energized causes closure of contacts 87, 88.

In the operation of this embodiment of the invention closure of the starting switch 53 causes energization of the starting motor through the resistor 55 whereby the screw shaft 59 is rotated. At the same time the coil 82 of the detent 78 is energized by current traversing leads 67, 83, coil 84 and lead 85 whereby the plunger 79 is caused to engage the teeth of pinion 63 to resist its rotation and thus ensure its traversal into engagement with the engine gear 64. The coil 82 is also energized by current traversing leads 67, 74, coil 73 of relay 65 and lead 75, but the coils 84 and 73 are so designed that the current traversing these coils when they are thus in series with the detent coil 82 is insufficient to cause coil 84 to close contacts 87, 88, or coil 73 to cause closure of contacts 66, 71, 68.

When the pinion 63 is completely meshed with the engine gear and its traversal arrested by the stop 93, the starting motor is stalled by the resistance of the engine to rotation. The voltage drop across the resistor 55 thus increases to a maximum which is sufficient to energize coil 91 of relay 77 to cause closure of contacts 87, 88. The detent 78 is thereby released by the deenergization of coil 82, and at the same time the coil 84 is fully energized so as to hold contacts 87, 88 closed, and coil 73 is also fully energized so as to cause closure of magnetic switch 65, thus bridging the resistor 55 and causing energization of the starting motor by the full battery voltage.

Cranking of the engine thereupon takes place, the parts being maintained in the stated positions as long as the starting switch 53 is held closed. When the engine starts and the operator opens the starting switch, the parts are returned to their idle positions as illustrated.

Although certain embodiments of the invention have been shown and described in detail, it will be understood that other embodiments are possible and various changes may be made in the design and arrangement of the parts without departing from the spirit of the invention as defined in the claims appended hereto.

What is claimed is:

1. In an engine starting system a starting motor, a power shaft driven thereby, a pinion threaded on the power shaft, a detent for re-

sisting rotation of the pinion, electromagnetic means for actuating the detent energized simultaneously with application of current to the starting motor, and means responsive to the assumption of the cranking load by the motor for causing release of the detent.

2. In an engine starting system a starting motor, a power shaft driven thereby, a pinion threaded on the power shaft, a detent for resisting rotation of the pinion, electromagnetic means for actuating the detent energized simultaneously with application of current to the starting motor, means including a relay for de-energizing said electromagnetic means, and means responsive to completion of the driving connection from the motor to the engine for actuating said relay.

3. In an engine starting system a starting motor, a power shaft driven thereby, a pinion threaded on the power shaft, a detent for resisting rotation of the pinion, electromagnetic means for actuating the detent energized simultaneously with application of current to the starting motor, means including a relay having a pair of contacts, closure of which effects de-energization of the electromagnetic means, and means responsive to the stalling of the starting motor for closing said contacts and holding them closed as long as the starting motor remains energized.

4. In an engine starting system a starting circuit including a starting switch, a resistor and a motor in series therewith, a power shaft driven by the motor, a pinion having a threaded connection with the power shaft, a detent for resisting rotation of the pinion to ensure its traversal when the power shaft rotates, electromagnetic actuating means for the detent energized by closure of the starting switch, means responsive to the voltage drop across the resistor when the starting motor stalls for de-energizing said electromagnetic means and for shorting out the resistor, and means for maintaining the electromagnetic means de-energized thereafter as long as the starting switch remains closed.

5. In an engine starting system a starting circuit including a starting switch, a resistor and a motor in series therewith, a switch for bridging the resistor, a power shaft driven by the motor, a pinion having a threaded connection with the power shaft, a magnetically operable detent for resisting rotation of the pinion to ensure its traversal, means energized by closure of starting switch for actuating the detent, and means including a relay having a coil in shunt with the resistor and energized by the voltage drop across the resistor when the starting motor stalls to effect release of the detent and to close the bridging switch.

E. ELLIOTT HOOD.
